UNITED STATES PATENT OFFICE.

GEORGE C. BENTZINGER, OF ST. LOUIS, MISSOURI.

DESIGN FOR A BRUSH.

SPECIFICATION forming part of Design No. 30,616, dated April 25, 1899.

Application filed March 16, 1899. Serial No. 709,381. Term of patent 7 years.

To all whom it may concern:

Be it known that I, GEORGE C. BENTZINGER, a citizen of the United States, residing at St. Louis, State of Missouri, have invented and produced a new and original Design for Brushes, of which the following is a specification, reference being had to the accompanying drawing, forming a part thereof.

The figure is a perspective view of a brush, showing my new design.

The leading feature of my design consists in a body portion having longitudinal flat walls and outwardly-curved end walls, the top of the said body portion being flat and depressed below the upper edges of said walls, a loop extending vertically or on a line with the upper edge of one of the longitudinal walls and rivet-heads projecting from the outer surface of the longitudinal wall adjacent to the lower edge of the body portion.

Referring to the drawing, 1 represents the body portion of the brush, which is adapted to be grasped by the hand, the same consisting of flat longitudinal side walls 2 and outwardly-curved end walls 3. The top of the body portion 1 is flat and is depressed below the upper edges of the walls 2 and 3, as shown

at 5, the depression being substantially the same shape as the said body portion. Extending from one of the upper edges of the side walls 2 is a loop 6, which is substantially on a plane with the said wall, the shape of which corresponds to the shape of the top wall 5 of the body portion. Projecting from one of the flat walls 2, adjacent to the lower edge thereof, are rivet-heads 7. The bristles of the brush 8 extend below the body portion and form a permanent part thereof.

A brush designed as above described can be used for thoroughly cleaning the inside of any design of cooking utensil, its shape being of such a nature that it can be readily turned within the utensil in order that the brush proper can be applied to all parts.

What I claim is—

45

The design for a brush, substantially as herein shown and described.

In testimony whereof I affix my signature in presence of two witnesses.

GEORGE C. BENTZINGER.
